MEANS FOR EMBOSsing AND PRINTING

Kurt P. Reimann, Rutherford, N. J.

Application January 31, 1951, Serial No. 208,749

1 Claim. (Cl. 101—25)

1

This invention relates to a method and means for forming, molding or embossing and/or printing a continuous roll of flexible material.

At present, the transfer of a design or a molded part to a roll of flexible material is accomplished with embossing and printing rollers in separate operations involving considerable labor and cost.

It is the object of this invention to provide a relatively inexpensive substitute for the known embossing and printing rollers together with the requisite accessory equipment for the utilization thereof.

A further object is to combine the embossing or forming and printing steps in one operation.

Another object is to decrease costs in the manufacture of molded and/or printed flexible goods in order that the benefits thereof can be brought to a greater number.

Other objects of the instant invention will become apparent in the course of the following specification.

In the attainment of these objectives, the device is constituted of an endless screen in which the transferable designs or patterns or characters are woven or attached, the points of the design being sufficient for the molding of the flexible material and/or the transfer of the design in ink. The endless screen is rotatably passed in the manner of a belt around a cylinder and a roller so that a portion of the screen is superposed upon a portion of the cylinder. An endless blanket is rotatably superposed upon a portion of the screen around the cylinder and the flexible material to be treated is passed between the superposed screen and blanket around the cylinder. By applying ink to the screen and the screen and blanket and flexible material moving together around the cylinder, the outline of the screen is molded in the flexible material by heat and pressure and/or imprinted.

The invention will appear more clearly from the following detailed description when taken in conjunction with the accompanying drawings showing by way of example a preferred embodiment of the inventive concept.

In the drawings:

Figure 1 is a cross sectional view of the molding and printing device for a continuous roll of flexible material constructed in accordance with the principles of this invention:

Figure 2 is a fragmentary view of one screen used in the device of Figure 1 for transferring a design to the flexible material; and

Figure 3 is a fragmentary view of another screen used in the device of Figure 1.

2

Referring now in greater detail to the drawings where like reference numerals indicate like parts, reference numeral 10 indicates the screen, 11 the blanket and, 12 the cylinder.

The screen 10 is woven in the usual manner from any suitable material and has in the weave such raised points as the points of connection 31 of the strands shown in Figure 3, or may have the points raised along the outline of the flower 32 shown in Figure 2, the design of the flower being attached to the screen. The screen 10 is further formed into an endless belt and is rotatably passed around the following described cylinder 12 and the roller 14 in the manner of a belt.

The cylinder 12 is a hollow drum which may be closed at both ends for the introduction of steam and is keyed to a shaft 13 journaled in any desired manner between two supports (not shown).

The roller 14 is rotatably supported parallel to the shaft 13 of the cylinder and is spaced from the outer surface thereof as illustrated.

Coacting with the roller 14 is the auxiliary roller 15 also rotatably mounted parallel to the shaft 13 and in tangential contact with the roller 14 as further illustrated. By this construction, the screen 10 passes around a portion of the cylinder 12, and between the roller 14 and the auxiliary roller 15. By imparting rotary motion to the shaft 13 or to the roller 14 or both, the screen and the cylinder and the rollers are simultaneously rotated.

Superposed upon a portion of the screen 10 around the cylinder 12 is an endless blanket 11. The blanket 11 is of known material and is rotatably passed around the rollers 16 and 17 with a part of the inner portion superposed upon the screen and with the remainder or outer portion in spaced arrangement around a part of the periphery of the cylinder. The roller 16 is in tangential contact with the screen while the roller 17 is spaced from the screen, the rollers 16 and 17 being on opposite sides of the roller 14 and intermediate the shaft 13 and the roller 14. Maintaining the outer portion of the blanket in spaced arrangement around a part of the periphery of the cylinder are the similar rollers 18 rotatably supported in a known manner parallel to the shaft 13.

Intermediate the auxiliary roller 15 and the blanket roller 16 is the inking roller 19 which is rotatably mounted and coacts with an inking trough 20, the roller 15 being in tangential contact with the screen as shown. The inking roller 19 may be provided with the known doctor blade 21 for the elimination of excess ink.

Maintaining the blanket 11 under tension against the screen 10 and the cylinder 12 are the rotatably mounted rollers 22 and 23 which are maintained axially adjustable relative to the shaft 13 of the cylinder by any suitable means.

For example, at one end the rollers may be journaled in an axially adjustable support 24 spaced below the blanket and at the opposite end by a similar support while a tension adjustment mechanism 25 at both ends of the rollers having a spring 26 intermediate the end support of the rollers and an anchor 27 will vary the tension of the rollers against the blanket when the screw 29 is threaded in and out of the support.

The continuous roll of imprintable flexible material 33 is passed around the roller 16 and fed between the screen 10 and the blanket 11 around the cylinder and thence between the roller 14 and a coacting roller 30 as illustrated.

In operation:

The shaft 13 of the cylinder and/or the rollers 14, 16, 17, 18 and 30 may be driven rollers set into motion by any suitable means. The design of the screen shown in Figure 3 is formed by the interconnection of the strands being especially pronounced and inked when the impression of both the strands and the connecting points is transferred by the coaction of the pressure rollers 22 and 23 and the heat of the cylinder is raised to around 250° F. by any suitable device 34. The ink being on the high spots, the interconnecting points of the strands will be both molded and inked in the final product. If desired, more than one set of the pressure rollers illustrated and described may be used.

It will be understood that the invention is not limited to the exact disclosure herein described but may lend itself to a variety of expressions within the scope of the appended claim.

What is claimed is:

A forming and printing device for a continuous roll of flexible material, said device comprising a hollow drum adapted to be heated, two blanket-engaging rollers located adjacent to the surface of

the drum at a distance from each other which is less than the diameter of the drum, other blanket-engaging rollers located on the side of the drum which is opposite to the first-mentioned rollers, the second-mentioned rollers being spaced around a portion of the periphery of the drum, a screen-engaging roller located between the two first-mentioned rollers, an endless screen engaging the last-mentioned roller and also engaging said portion of the periphery of the drum, an endless blanket engaging the first- and second-mentioned rollers and pressed by the first- and second-mentioned rollers against said portion of the periphery of the drum, an auxiliary roller located between the last-mentioned roller and one of the two first-mentioned rollers for tensioning said screen, an inking roller located between the auxiliary roller and said one of the two first-mentioned rollers and engaging said screen, a roll-feeding roller located adjacent the screen-engaging roller and coacting therewith to feed a roll between said screen and said blanket upon said portion of the periphery of the drum, and a blanket-tensioning device engaging said blanket between two of the second-mentioned rollers.
